UNITED STATES PATENT OFFICE.

THOMAS S. ALLEN, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

DYNAMO-ELECTRIC MACHINE.

1,085,316.

Specification of Letters Patent.

Patented Jan. 27, 1914.

Application filed February 28, 1910. Serial No. 546,540.

To all whom it may concern:

Be it known that I, THOMAS S. ALLEN, a citizen of the United States, residing at Milwaukee, in the county of Milwaukee and 5 State of Wisconsin, have invented certain new and useful Improvements in Dynamo-Electric Machines, of which the following is a full, clear, and exact specification.

This invention relates to dynamo-electric 10 machines and particularly to improvements in the construction and means for cooling commutators of machines of high speed and large current output such as turbo generators.

15 It is a well known fact that the commutators of high speed machines of large current output must be made relatively small in diameter, and that even though such commutators are given considerable length, 20 the segments tend to become hot due to the high brush friction and contact losses. In such machines considerable difficulty has been experienced in supporting the segments in a manner such that they will not 25 buckle or be distorted or otherwise shifted from position, and it has also been difficult to cool the commutator in a satisfactory manner and to prevent a rise in temperature which would affect the efficiency and operation 30 of the commutator and brushes.

One of the objects of the invention is to provide commutator-supporting means which permits a good circulation of air through the interior of the commutator, 35 which is very effective for securely holding the segments in place, which is simple in construction, inexpensive to manufacture and assemble, and which permits an adjustment and a tightening of all the parts.

40 A further object is to secure a more effective cooling of a commutator than has been possible heretofore, so that the life of the commutator and brushes will be prolonged and their efficiency and operation 45 will be improved.

To the end of securing these and other objects hereinafter appearing, I have provided an improved construction, in carrying out my invention, consisting in certain novel de- 50 tails and combinations and arrangements of parts which will be described in the specification and set forth in the appended claims.

In the accompanying drawings, Figure 1 is a partial elevation and partial longitudi-

nal sectional view of a commutator constructed in accordance with my invention, and of a portion of the armature of a dynamo-electric machine; Fig. 2 is a transverse sectional view substantially along the line 2—2 of Fig. 1, looking in the direction indicated by the arrow; Fig. 3 is a top plan view of a portion of the shaft and of the supporting means for the outer end of the commutator; and Fig. 4 is a sectional view taken through a portion of the combined commutator necks and fan blades.

Referring now to the figures of the drawing, 10 represents a portion of the armature, and 11 the shaft of a direct current dynamo-electric machine, such as a turbo-generator 70 or other direct current machine of large current output, having a long commutator, the segments of which are shown at 12.

In order that the segments may be supported in an effective and satisfactory manner, and so as to permit a good circulation of air through the interior of the commutator, I provide at the ends of the commutator two sets of supporting arms or members which project radially outward from the shaft. 80 Preferably at the inner end of the commutator the supporting arms, which are shown at 13, are integral with the shaft and are formed by slotting an inclined or tapered portion of the stock from which the shaft 85 is formed, so that the arms have downwardly and outwardly tapered outer surfaces and air spaces 14 are formed between the arms. At the outer end of the commutator the supporting arms are preferably adjustable and 90 consist of wedges or tapered members 15 which have downwardly and inwardly tapered outer surfaces and are axially movable in slots 16 provided about the surface of the shaft. These members 15, which are 95 spaced apart so that open air spaces are provided between them, may be shifted inwardly and are held securely in position after adjustment by nuts 17 which engage a threaded portion 18 of the shaft.

100 Resting on the outer tapered surfaces of the two sets of arms 13 and 15 respectively are tapered or conical sleeves 19 and 20, which are preferably expansible, in this case each being split diagonally or provided with 105 an inclined slot 21, so when the wedges 15 are forced in by means of the nuts 17 the sleeves 20 and 19 will expand and grip the

- insulation 22 so that all the sliding movement will be between the metal sleeves 20, 19 and the wedges 15, 18, thereby causing no displacement of the insulation 22. The 5 sleeves 19 and 20 support the segments 12 which are separated from the sleeves by suitable insulation 22, and which may be clamped to the sleeves and prevented from buckling by any suitable clamping devices 10 such as shrink rings 23, three of which are shown in the drawings. The portions of the inner surfaces of the segments opposite the sleeves are tapered or inclined in accordance with the inclination of the sleeves, 15 so that the segments will be firmly seated and will be held against endwise movement. Because of the particular construction of the segment supporting means, air may circulate freely through the commutator between 20 the arms 13 and between the arms 15 and along the inner surface of the commutator between the segments and the shaft. In order that there may be a good continuous circulation of air through the interior 25 of the commutator while the machine is in operation, any suitable ventilating means may be employed, but in this case I arrange the commutator necks 24 which connect the segments 12 and coils 25 of the armature 30 winding, so that they will, in addition to carrying a current between the coils and the segments, act as fan blades. This is accomplished by skewing or inclining the blades with respect to the axis of the machine so 35 that, when the machine is in operation and is rotated in the direction indicated by the long arrow in Fig. 4, air will be drawn through the interior of the commutator from the outer to the inner end, and will be dis- 40 charged in the direction indicated by the shorter arrows in Fig. 4 over the outer surface of the commutator. In this manner the segments can be very effectively cooled.
- Not only do the segment supporting means 45 permit of a good circulation of air through the interior of the commutator, but, with the construction which I have provided, the segments are securely held in position, and the segments or supporting means can be 50 adjusted, if adjustment is desired, because of the construction at the outer end of the commutator. Furthermore the commutator and the supporting means can be very easily assembled or taken apart when necessary.
- 55 I do not desire to be confined to the exact details shown, but aim in my claims to cover all modifications which do not involve a departure from the spirit and scope of my invention.
- 60 What I claim as new and desire to secure by Letters Patent is:—
1. In combination, in a dynamo-electric machine, a shaft, a commutator comprising a plurality of segments, means for supporting the segments and spacing them from the
- shaft comprising two sets of arms with air spaces between the arms of each set, said air spaces communicating freely through openings as large as themselves with the space between the shaft and the segments and with the atmosphere, sleeves resting on the arms and forming seats for the segments, and means for clamping the segments to the sleeves. 70
2. In a commutator construction, a shaft, 75 a commutator comprising segments, two sets of arms extending outwardly from the shaft and spaced apart by distances which are fully as wide as the arms, adjustable sleeves supported on said arms, and means for 80 clamping the segments to the sleeves.
3. In a commutator construction, a shaft, a commutator comprising commutator segments, two sets of radial arms projecting outwardly from the shaft and provided with 85 tapered outer surfaces, split tapered sleeves supported on the arms, each set of arms comprising a plurality of parallel, spaced and axially-disposed arms to provide a through passage from one end of said commutator 90 to the other beneath said segments, and means for clamping the segments onto the sleeves.
4. In a commutator construction, a shaft, 95 a plurality of commutator segments, means for supporting the commutator at each end thereof, the supporting means at one end of the commutator comprising an integral tapered portion of the shaft which is slotted forming supporting arms and air spaces between the arms, and a split conical sleeve resting on said arms and forming a seat for the segments. 100
5. In a commutator construction, a shaft, 105 a plurality of commutator segments, a shaft extending through the commutator, means for supporting the commutator so as to provide an unobstructed passage between said commutator segments and said shaft and comprising a plurality of independent, circumferentially-spaced, axially-movable tapered members, an expansible sleeve supported by 110 said members, and means for clamping the segments to said sleeve.
6. In a commutator construction, a plurality of segments, a shaft extending through the commutator and provided with a plurality of axially arranged slots, a plurality of radially extending tapered members engaging said slots, an expansible 115 sleeve supported on said members, and means for clamping the segments to the sleeve. 120
7. In combination, in a dynamo-electric machine, a shaft, a commutator comprising 125 a plurality of segments, means for supporting the commutator at each end, said supporting means comprising two sets of radial arms with tapered outer faces, one set being integral with the shaft, and the other set 130

being supported thereby and adjustable in an axial direction, tapered expansible sleeves supported by the arms, and means for clamping the segments to the sleeves.

8. In combination, in a dynamo-electric machine, a shaft, a commutator comprising a plurality of segments, means for supporting the commutator at each end, said supporting means comprising two sets of outwardly projecting arms spaced apart by distances fully as wide as themselves, sleeves resting on the arms and having the segments clamped thereon, and means for causing a circulation of air between the arms of each set and through the interior of the commutator.

9. In combination, in a dynamo-electric machine, a shaft, a commutator comprising a plurality of segments, means for supporting the segments so as to permit a free circulation of air through the interior of the commutator, said supporting means comprising two sets of members extending radially outward from the shaft adjacent opposite end of the commutator, the members of each set having air spaces between them, sleeves supported on said members and forming seats for the segments, rings surrounding the segments and clamping the latter to the sleeves, and means for causing a circulation of air through the air spaces between said members and through the interior of the commutator.

10. In a dynamo electric-machine, a commutator comprising a plurality of segments, a shaft, means for supporting said commutator segments on said shaft comprising

ing a plurality of spaced wedge elements mounted on said shaft and an expansible ring encircling said elements, and means including skewed commutator leads for causing air to enter the space between the shaft and the commutator segments at one end of the commutator, to leave it at the other end, and then to pass along the outside of the commutator in the other direction.

11. In a dynamo-electric machine, the combination of a shaft, an armature mounted thereon and provided with a winding, a commutator comprising a plurality of segments, supporting means for said segments comprising a plurality of spaced longitudinally extending elements mounted on said shaft adjacent said armature and an encircling ring on said elements, leads connecting said armature winding with said commutator segments, said commutator being spaced from said shaft by said supporting elements to provide a passage between the end of said commutator adjacent said armature and another point along said commutator, and fan means associated with said leads for causing a flow of ventilating fluid axially beneath said commutator segments toward said armature and in the opposite direction across said commutator surface.

Milwaukee, Wisconsin, February 18, 1910.

In testimony whereof I affix my signature, in the presence of two witnesses.

Correction in Letters Patent No. 1,085,316.

It is hereby certified that, in Letters Patent No. 1,085,316, granted January 27, 1914, upon the application of Thomas S. Allen, of Milwaukee, Wisconsin, for an improvement in "Dynamo-Electric Machines," an error appears in the printed specification requiring correction as follows: Page 3, line 25, for the word "end" read *ends*; and that the said Letters Patent should be read with this correction therein that the same may conform to the record of the case in the Patent Office.

Signed and sealed this 17th day of February, A. D., 1914.
